CLAIM

The ornamental design for a boot rack, as shown and
described.

DESCRIPTION

FIG. 1 is a perspective view of a boot rack;

FIG. 2 is a front elevation view thereof;

FIG. 3 is a rear elevation view thereof;

FIG. 4 is a right side elevation view thereof, the left side
elevation view being a mirror image thereof;

FIG. 5 is a top plan view thereof; and,

FIG. 6 is a bottom plan view thereof.

The broken lines shown in the drawings depict portions of
the boot rack that form no part of the claimed design.
